CLAIM

The ornamental design for paper towel holder, as shown and described.

DESCRIPTION

FIG. 1 is a top, front, and right side perspective view of a paper towel holder showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof, the left side being a mirror image of that shown; and.

FIG. 7 is a vertical cross-sectional view thereof, taken along line 7—7 of FIG. 2.

FIG. 1

FIG. 4
